UNITED STATES PATENT OFFICE.

CHARLES E. MAXWELL, OF WOLLASTON, MASSACHUSETTS.

TYPE-WRITER.

SPECIFICATION forming part of Letters Patent No. 696,833, dated April 1, 1902.

Application filed January 14, 1901. Serial No. 43,260. (No model.)

To all whom it may concern:

Be it known that I, CHARLES E. MAXWELL, a citizen of the United States, residing at Wollaston, county of Norfolk, State of Massachusetts, have invented an Improvement in Type-Writers, of which the following description, in connection with the accompanying drawings, is a specification, like letters on the drawings representing like parts.

10 My invention relates to type-writers, and especially that class of type-writers that are adapted to write upon a plain surface—such, for instance, as the page of a book.

Heretofore, so far as I am aware, all so-called "book" type-writers are of the type-bar kind; and it is the object of my invention to construct a type-writer adapted to write on the page of a book wherein a type-wheel is used instead of type-bars, the type-wheel being preferable, because a type-wheel type-writer is capable of more accurate alignment than a type-bar machine.

My invention comprises a base upon which is slidably mounted for movement longitudinally thereof a carriage, the said carriage carrying a printing mechanism and its supporting-frame, the said printing mechanism being movable upon the carriage transversely of the base. The printing mechanism includes a type-wheel, upon the surface of which the various characters and letters are placed, and suitable type-wheel rotating and vibrating mechanism, together with means operated by the type-wheel-vibrating mechanism, to advance the printing mechanism to form the space between each letter or between the words. The space between the lines is made by advancing the carriage bodily toward the front of the base by means of a line-spacer 40 consisting of a key-lever mechanism.

In the ordinary type-wheel type-writer the type-wheel has a cylindrical surface, upon which are a series of circular rows or fields of type—as, for instance, small case, capitals, figures, and symbols—such cylindrical shape of the type-wheel being operative, because the paper rests upon a cylindrical platen or surface.

In adapting a type-wheel for printing upon a plane surface it is necessary either to place all the symbols or characters upon a single field or zone on the surface of the type-wheel

or make the surface of the type-wheel with a plurality of type fields or zones at different angles to the axis of the wheel.

55

This invention is illustrated with a type-wheel of the latter class, which is constructed so as to have on its surface a plurality of type zones at different angles to the axis of rotation of the type-wheel, and suitable mechanism is employed to bring any one of the type zones into operative position—that is, into such position that the type on said type zone may be impressed upon the paper, and this without having any of the type in the other zones brought in contact with the paper. For this purpose the type-wheel is pivotally attached to a suitable vibrating arm, so as to be capable not only of rotation about its longitudinal axis, but also capable of swinging 70 about a transverse axis, the movement about the transverse axis operating to bring any one of the type zones into operative position or parallel with the paper. The movement of the type-wheel about its transverse axis is controlled by suitable key-lever mechanism.

Referring now to the drawings, Figure 1 is a plan view, with portions of the mechanism broken away, of a type-writer embodying my invention. Fig. 2 is a section on the line xx , Fig. 1. Fig. 3 is a detail showing the mechanism for bringing any type zone into operative position. Fig. 4 is a section on the line 4 4, Fig. 1, looking in the direction of the arrow. Fig. 5 is a section on the line 5 5, Fig. 1, looking to the right. Fig. 6 is a section on the line 6 6, Fig. 5. Fig. 7 is a detail herein-after referred to. Fig. 8 is a perspective view of a portion of the mechanism. Fig. 9 is a detail of the vibrating arm and rock-shaft to which the type-wheel is pivotally connected. Fig. 10 is a detail of the mechanism shown in Fig. 3. Figs. 11 and 12 are details of the type-wheel mechanism. Fig. 13 shows a modified form of type-wheel.

95

The base of the machine is designated generally by 3, and this is pivotally connected at one end to a suitable standard, comprising the fixed uprights 4, which are connected by a suitable rod 5. The rod 5 may be either telescopic, so as to permit of its being extended to span both pages of a book on which the type-writer is to be used, or the said rod may be solid and of sufficient length to reach across

100

both pages of the open book. The base 3 is pivotally connected to the rod 5 by means of the straps or links 6, which embrace the rod 5, as seen in Fig. 2, and are pivotally connected to the rod 7 at one end of the base 3. The rod 5 may be provided with suitable adjustable stops 8 for the purpose of preventing lateral motion of the base 3, the said stops being secured to the rod 5 by any suitable means, as by set-screws 9. If desired, the links 6 may be clamped to the rod 5 by the means illustrated in Fig. 2, which consists of the bolt passing through the two members of the link and having the arm 10, provided with a screw-thread aperture for clamping the loop of the link to the rod 5. With this construction when one page of a book has been written upon by loosening the clamping device 10 and the stop-coillars 8 the base may be moved bodily upon the rod 5 and shifted sidewise into position over the other page.

The base 3 is preferably made extensible, whereby the type-writer may be used upon different-sized books, if desired, and said base 25 comprises the outer U-shaped section 11, having the two side pieces and the front portion 12, provided with a suitable finger projection 13, and the inner U-shaped section 14, the two side portions of the section 14 being connected 30 together at one end by the rod 7.

Referring to Figs. 4 and 5, it will be seen that the side pieces of the section 11 are slotted and have the base-flange 15, which rests upon the paper or book, while the side sections 14 are provided with means for adjustably securing the two sections together—such, for instance, as screws 16, which pass through the slots in the side pieces 11 and screw in the side pieces 14. Each side piece 14 is provided with the inwardly-disposed rib 17, which serves as a guide for the carriage C, upon which the printing mechanism is supported. The carriage C comprises the two runners 18, which are suitably guided by the 45 rib 17 and the bridge-piece 19, connecting said runners, the bridge-piece forming a support upon which the printing-mechanism frame is carried, as hereinafter described. The runners 18 are shown as comprising an upright 50 portion, which is fastened at its upper end in any suitable way to the bridge-piece 19 and at its lower end is bent inwardly, as at 20, and extends under the rib 17, (see Figs. 4 and 5,) the said rib and co-operating flange 20 operating to hold the carriage firmly upon the base and yet to allow of its having a sliding motion thereon.

The line-spacing mechanism for advancing the carriage will be hereinafter described.

60 The printing-mechanism frame, which is supported upon the bridge 19 of the carriage C, may be of any suitable construction adapted to support the operative parts of the printing mechanism, and it is shown as having extending across the same centrally thereof the angle-bars 21, on which are mounted suitable friction-rollers 22, which rest against the

edges of the bridge-piece 19, as plainly seen in Figs. 1 and 2.

The front end of the printing-mechanism frame has extending across the same the angle-bar 23, to which is journaled antifriction-rolls 24, which rest upon a brace-piece 25, connecting the runners 18. It will thus be seen that while the carriage C is supported for movement longitudinally of the base the printing-mechanism frame is supported upon the carriage for movement transversely of the base, and the printing-mechanism frame moves upon the carriage during the writing of any line, while the carriage and frame are advanced toward the front of the base in order to write a new line.

The printing mechanism illustrated is that of a type-wheel mechanism, the type-wheel 85 being supported upon a rock-arm, which is given its movement by means of two vibrating sectors, as usual in type-writers of this class.

Inasmuch as the type-writer herein described is adapted for writing on plane or flat surfaces, it would be impossible to use a type-wheel having a plain cylindrical surface upon which were a series of rows or fields of type, for when the type-wheel was vibrated to make 95 an impression upon the paper one of the characters in each of the fields or rows of type would contact with and leave an impression on the paper.

My type-wheel instead of having a cylindrical surface has on its exterior a plurality of what I term "type zones," each type zone having thereon certain characters or symbols, and preferably one zone would have the small type thereon, another zone the capital letters, 100 and a third zone figures or symbols, although this arrangement is not necessary. Each type zone has a different angular relation to the longitudinal axis of the wheel, and the wheel is pivotally mounted upon a transverse axis, 105 and suitable mechanism is provided for swinging the type-wheel about such transverse axis, whereby any one of the type zones may be brought into operative position—that is, in such position that when the type-wheel is vibrated the symbols or characters in such zone 115 will strike the paper squarely.

Herein I have illustrated a type-wheel; but it will be obvious to those skilled in the art that a type-shuttle such as is used in the well-known Hammond type-writer might be employed instead of a type-wheel, such a modified form of type-wheel being illustrated in Fig. 13, and I desire it understood that herein the term "type-wheel" is used in its broad 125 sense as including either a type-wheel of the class shown in the main views of the drawings or a type-shuttle, as illustrated in Fig. 13, or any other device wherein the type are all arranged upon a single rotatable support. 130

In a type-wheel type-writer wherein the paper is supported on a cylindrical surface or platen it is necessary that the face of the type be concaved in order to fit the convex

surface of the platen; but in my type-writer, wherein I write on a plane surface, I make the face of the type flat, so that each character will be squarely impressed on the paper.

- 5 The type-wheel is designated by 26, it having on its surface a plurality of type zones, as above described, and being pivotally connected to the vibrating arm 27 in a manner hereinafter described, the arm 27 being fast 10 at one end in a transverse aperture in the rock-shaft 28. (See Figs. 7 and 9.) The said rock-shaft 28 is sustained at each end upon suitable pivot-pins 29 by having concentric sockets bored in the ends of said rock-shaft in 15 which the ends of the said pivot-pins rest, as plainly seen in Fig. 9, the said pivot-pins being suitably supported in the printing-mechanism frame, the frame for this purpose having the depending arm 30, through which the said pins 20 pass and in which they are supported, the ends of the pins being supported for rotative movement in any suitable way in the side members of the printing-mechanism frame. The rock-shaft 28 has sleeved thereon the hubs of the 25 sectors 31, which sectors have gear-teeth meshing with a pinion 32, loose upon the rock-arm, said pinion having mechanism connecting the same to the type-wheel, whereby rotation of the said pinion is transmitted to the 30 type-wheel, as is usual in this class of devices. The rocking of the sectors 31 is accomplished by means of the usual bails 33, which are pivotally mounted upon the bar 34, there being one bail for each sector 31, as usual, each 35 bail having an arm 35 integral therewith and projecting therefrom, which arm has at its end the gear-teeth 36, meshing with co-operating gear-teeth upon the respective hubs of the sectors 31, this construction being common 40 in type-wheel type-writers. The bails are operated by the usual key-levers, which are fulcrumed upon the rod 34 and are maintained in their inoperative or raised position by means of the usual springs 37. A second 45 bail 39, extending clear across the printing-mechanism frame and also pivotally mounted upon the bar 34, has an arm 40 connected thereto centrally thereof, said arm being also pivoted upon the bar 34 and having at its end 50 gear-teeth which mesh with gear-teeth 41 upon a sleeve 42 on the rock-shaft 28 between the hubs of the two sectors, which sleeve carries a locking-arm 43, which co-operates with the heart locking-wheel 44, integral with the pinion 32, this locking mechanism for the type-wheel being of familiar construction. Inasmuch as the sleeve upon which the locking-arm 43 is mounted has a motion around the shaft 28, I provide the said sleeve with oppositely-disposed slots 42', through which the vibrating arm 27 extends, these slots permitting the said vibrating arm 27 and the shaft 28 to move independently of the sleeve 42. It will of course be obvious that each key-lever will have directly over the bail 39 a notch 45 of suitable depth, so that the bail 33 will be operated to bring the desired charac-

ter in proper position to be impressed upon the paper before the locking-arm is thrown into operative engagement with the heart-wheel.

It will be understood, of course, that suitable spring mechanism may be employed to return the bails to their normal position as soon as the depressed key has been released, such springs acting through the bails to raise the type-wheel from the paper. I may, if desired, provide suitable springs 29' to assist in this operation, the springs being shown as surrounding the end of the rock-shaft 28 and as fast thereto at one end and at the other end to the sleeve-hub of the sectors 31. These springs 29' will operate to return that sector which has been depressed farthest back into its normal position, even with the other sector, and the spring mechanism underneath the bails will operate to throw both sectors and the type-wheel back into their normal position.

Further description of the type-wheel rotating and vibrating mechanism is not deemed necessary, as such mechanism is common in this art.

As usual in type-wheel type-writers, a suitable ink pad or roll (or ribbon, if desired) is provided, against which the type-wheel contacts just before it strikes the paper, said inking-roll operating to ink the letter or character which is to be impressed upon the paper.

In this invention the usual ink-roll 150 is shown as mounted upon the pivoted arm 151, which is suitably connected to the frame of the printing mechanism, said arm being controlled by the spring 152, as usual.

Preferably the yoke 47, which supports the type-wheel, as hereinafter described, will have a transverse member or shield 70, against which the inking-pad rolls when the type-wheel is fully depressed.

As stated above, the type-wheel has on its surface a plurality of type zones, and in this embodiment of my invention the said type zones are represented by cylindrical and conical surfaces, there being three such zones, designated by *a*, *b*, and *c*, respectively. In a type-wheel of the style shown the flat face of the type will be approximately parallel to the zone surface. I wish it understood, however, that I may make the surface of the type-wheel in the shape of a sphere or in any other shape, provided the faces of the type themselves are flat in all instances. In order to bring any one zone into operative position, the said type-wheel is mounted upon an axis transverse to its longitudinal axis, one convenient way of thus mounting the type-wheel being shown, wherein a frame or yoke 47, having a spindle 48 projecting therefrom and upon which the type-wheel is mounted for rotation, has the ends of its arms pivotally connected to the arms of a yoke 49, which is fast upon the vibrating arm 27, the yoke 49 being illustrated as being connected to the said vibrating arm 27 by the gooseneck 50,

though this particular construction is not necessary. The pivotal points 51 between the arms of the yokes 49 and 47 are illustrated as being on a line approximately at right angles to the longitudinal axis of the type-wheel and central of said wheel, although this is not necessary, as the transverse axis upon which the type-wheel swings might be either side of the center thereof. One of the arms of the yoke 47 has projecting therefrom an offset 51', to which is connected a link 52, said link being given a suitable longitudinal movement by a suitable key-lever mechanism, hereinafter described, to turn the type-wheel about its transverse axis 51 for the purpose of bringing either of the type zones into operative position. As illustrated in Figs. 2 and 3, the central type zone *b* is the operative one.

The key-lever mechanism for turning the type-wheel about its transverse axis will now be described, referring particularly to Figs. 3 and 10. A key-lever 53 is pivotally mounted, as at 54, upon the printing-mechanism frame and has connected thereto the link 55, which is pivotally connected to an arm 56 upon a sleeve 57, carried by the pivot-pin 29 for the rock-shaft 28. The sleeve 57 has at one end a flange or disk 58, which co-operates with the flange or disk 59 upon a sleeve 60, also carried by the pin 29, the disk 58 having a shoulder which engages a projection upon the disk 59, so that the forward rotation of the said disk 58 is communicated to disk 59; but the said disk 58 and sleeve 57 may turn back into their normal position without affecting the disk 59 and sleeve 60, a spring 57' being provided for returning them to their normal position and a similar spring 60' acting similarly for the sleeve 60. The sleeve 60 has the arm 61 integral therewith, the said arm being connected to the arm 62, pivotally mounted upon the pin 29, and the arm 62 is in turn connected to the link 52. By means of this construction it will be seen that when the key-lever 53' is depressed the link 55 will operate to turn the sleeve 57, and through the mechanism described and illustrated in Fig. 10 give to the link 52 a longitudinal motion to thereby turn the type-wheel about its transverse axis. A suitable stop-pin 63, made fast to the printing-mechanism frame, serves to limit the depression of the key-lever 53, and any suitable mechanism may be employed to lock the said lever in its depressed condition, so as to hold the desired type-zone in operative position.

Assuming that the type zone *a* is that containing the small letters, it will be obvious that mechanism must be employed to bring either the type zone *c* or *b* into operative position, and this is accomplished by providing the key-lever 53 with a supplemental key-lever 65, pivotally connected thereto, as at 66, and resting upon a pin or projection 67, fast upon the main key-lever 53. A stop-pin 63' is employed to limit the depression of the supplemental key-lever 65, the stop-pin 63' being

slightly longer than the stop-pin 63. With this construction it will be obvious that to bring the type zone *b* into operative position 70 the key-lever 65 is used, the said key-lever by means of its connection with the key-lever 53 operating to depress the same until it strikes the stop-pin 63'.

When the type zone *c* is to be brought into operative position, the key-lever 53 is depressed by its key 53', and as the stop-pin 63, co-operating therewith, is shorter than the stop-pin 63' the said key-lever may be depressed sufficiently to bring the type zone *c* into operative position.

As stated above, the type-wheel is rotated from the pinion 32 by means of an arm, the said arm being designated by 67, and it having a universal-joint connection with the 85 type-wheel, such connection being necessary because of the movement of the type-wheel about its transverse axis. One convenient way of making this universal joint is as illustrated in Figs. 11 and 12, wherein the arm 90 67, which has a pivotal connection with the pinion, is slotted, as at 68, and the type-wheel is provided with the pin 69, having the reduced portion which plays in the slot 68.

It will be obvious, of course, that other forms 95 of universal joint may be employed, if desired.

It is sometimes desirable to limit the movement of the type-wheel about its transverse axis, and this is conveniently accomplished by providing the yoke 47 with the transverse 100 guide-piece 70 or shield, said guide-piece or shield having shoulders or stops 71 thereon, which co-operate with a shoulder upon a spring-arm 72, fast to the gooseneck 50. The shoulder 71 and the shouldered arm 72 co- 105 operate to limit the swinging movement of the type-wheel about its transverse axis in an obvious way.

The mechanism for producing the spacing 110 between the letters and between the words comprises a toothed bar fast upon the carriage C and a reciprocating pawl engaging the same, said reciprocating pawl being connected to the printing-mechanism frame and being operated both by mechanism common 115 to all the key-levers and by a separate space-lever, whereby the printing-mechanism frame is advanced one space each time a letter is impressed upon the paper and also may be advanced independently by the space-bar. 120

The bridge 19 has fast thereto at its under side the toothed bar 90 and the printing-mechanism frame supports the reciprocating feed-plate 91 in any suitable way, said feed-plate projecting at one end beneath the bridge 125 19, as seen in Fig. 2, and having pivotally connected to such projecting end the feed-pawl 93, said pawl having a tooth 94 to engage the notches of the bar 90 and being held in operative position by suitable spring 95. 130 The feed-plate is provided with a slot 96, through which projects one end of an operating-lever 97, said operating-lever being pivotally connected to a bracket 98, fast upon

the front comb 99 of the printing-mechanism frame and having the arm 100 projecting therefrom, which is adapted to be operated by the locking-bail 39, the bail for this purpose having a slot cut therein; in which the projection 100 normally plays, as best seen in Fig. 8. With this construction it will be obvious that when any key is depressed the locking-bail 39 will operate the projection 100 and swing the lower end of the operating-lever 97 toward the front of the machine, thereby moving the feed-plate 91 in the same direction and allowing the feed-pawl 93 to click into the next notch in the notched bar 90.

15 A suitable spring 101, connected to the printing-mechanism frame, bears against a pin or projection 102 upon the front of the feed-plate 91, and said spring operates to restore the feed-plate to its normal position as soon as the depressed key-lever is released. It will be obvious that as the feed-plate moves to the right in Figs. 2 and 8 the feed-pawl engaging the notched bar 90 will operate to advance the entire printing mechanism into position to impress the next letter upon the paper.

20 A stop-pawl 103, pivotally mounted upon the printing-mechanism frame, operates to engage the notches in the notched bar 90 and prevent any backward or retrograde movement of the printing-mechanism frame.

25 A separate space-bar independent from the other key-levers is provided for making the spaces-between the words, such space-bar being designated by 105 and having at one side thereof the cam projection 106, which bears upon the upper portion of the operating-lever 97; as seen in dotted lines in Fig. 8. By depressing this space-lever 105 it will be obvious that the printing mechanism can be advanced to form the space between the word without operating the type-wheel.

30 The line-spacing mechanism is carried by the printing-mechanism frame, and consists of a key-lever mechanism in operative connection with a gear wheel or pinion upon the carriage C, which gear-wheel meshes with a rack-bar upon the base of the machine. As illustrated, the rib 17 (see Fig. 4) is provided 35 with gear-teeth upon its upper surface, and hence operates as a rack-bar, and the carriage C is provided with a transverse shaft 80, which has fast thereon a gear-wheel 81, meshing with the gear-teeth upon the rib 17. A suitable pawl-and-ratchet mechanism is used 40 to intermittently rotate the gear 81, said pawl-and-ratchet mechanism being controlled by the key-lever mechanism upon the printing-mechanism frame. One convenient arrangement of this pawl-and-ratchet mechanism is illustrated in Figs. 4, 5, and 6, wherein the gear-wheel 81 has fast thereon the disk 82, provided with a milling-surface, and thus operating as a ratchet-wheel, and the shaft 80 45 has pivotally mounted thereon an arm 83, to which is pivotally attached a pawl 84, which

cooperates with the milling-surface of the disk 82. The shaft 80 has mounted thereon a sleeve 110, which is rigidly connected to an arm 111 for turning movement about the shaft 80, the said arm 111 having the offset portion 112, which engages the end of the pawl 84, as seen in Figs. 4 to 6. It will be obvious that with this construction whenever the sleeve 110 is turned about the shaft 80 the arm 111, through its offset portion, will rock the pawl 84 and bring its nose into engagement with the milled surface of the disk 82, when further rotation of the sleeve 110 will operate to turn the gear-wheel 81, and thus advance the carriage C.

For the purpose of turning the sleeve 110, which sleeve is in the nature of a rock-shaft, the said sleeve is provided with a longitudinal projection or fin 115, which is engaged by a reciprocating rod 116, operated by a suitable key-lever having a projection 117 depending therefrom, which is pivotally connected to a lever 118, to the end of which the rod 116 is pivoted, the lever 118 being pivotally connected in any suitable way to the printing-mechanism frame. The end of the rod 116 which engages the fin or projection upon the sleeve 110 may be enlarged somewhat, if desired, so as to have a firmer bearing upon the edge of said projection. With this construction the depression of the proper key-lever will, through its projection 117, operate the lever 118, and, through the rod 116, turn the sleeve 110, which sleeve, through the mechanism above described, will operate to turn the gear-wheel 81, and thus advance the carriage.

The projection 115 extends the full length of the sleeve 110, and the end of the rod 116 has a sliding engagement therewith, so that an operative connection between the line-spacing key-lever and the gear-wheel 81 is always maintained, regardless of the position of the printing mechanism. It will thus be seen that I have provided a line-spacing mechanism consisting of a key-lever device upon the printing-mechanism frame, this being quite an advantage, because the said line-spacing mechanism is easily operated without any reaching on the part of the operator.

In order to obtain different distances between the lines, I have provided an adjusting device which cooperates with the pawl-and-ratchet mechanism above described, such adjusting device being illustrated best in Fig. 6, wherein the arm 83 is shown as projecting beyond the shaft 80 on the opposite side, as seen in dotted lines at 120, and the bridge 19 of the carriage C has secured therein the adjustable screw 121, the said screw having the check-nut 122 for locking it in any adjusted position. A spring 123, secured at one end to the arm 120 and at the other to the bridge 19 of the carriage, serves to return the arm 83, and consequently the pawl 84, to its inoperative position. It will be evident that by ad-

justing the screw 121 the extent of the effective engagement of the pawl with the ratchet or milled wheel 83 may be adjusted, and consequently the distance that the carriage is advanced between the lines can be regulated.

In order to indicate when the end of the line is reached, the shaft 80 is provided at one end with a bell 125, and the printing mechanism has suitably supported thereon a hammer in such a position that as the end of the line is nearly reached the said hammer will strike the bell, and thus indicate this fact to the operator. The hammer is seen in Fig. 4 at 126, and it is pivotally mounted upon the printing-mechanism frame at one side of the center thereof and directly over the shaft 80, and said bell has attached thereto the pivoted pawl 127, having a nose or projection 128, engaging a stop or pin 129 upon the hammer 126. With this construction it will be seen that as the printing-mechanism frame and the bell-hammer move to the left in Fig. 4 the pawl 127 will ride over the upper edge of the bell 125 and be turned thereby, the nose 128 raising the hammer 126. As soon as the pawl 127 has moved past the outer edge of the bell the hammer will fall and strike the bell, thus giving the proper indication.

When the printing-mechanism frame is moved back in position to begin a new line, it will be obvious that the bell striking the pawl 127 will merely swing the same aside without causing the hammer of the bell to operate.

The printing-mechanism frame is shown as having the bowed portion 130, said bowed portion serving to strengthen the frame, and although acting as a guard for the type-wheel, preferably this bowed portion will be formed at one end, as at 131, with a curved rest, which is of such a height that when the front end of the base 3 is raised and the base is swung about the pivot-rod 7 the said rest 131 will engage the rod 5 of the standard, and thus the carriage and printing mechanism is firmly supported while the base is being lifted for the insertion of a book or other plane writing-surface underneath.

I may, if desired, employ a suitable scale 132, which will be fast with the rod 7 of the base 3, the said scale resting upon the upper edge of the plane surface which is being written upon, and thus assisting the operator in tabulating, &c.

I do not intend to limit myself to the constructional details of the present embodiment of my invention, as many changes may be made without departing from my main invention, and accordingly I do not limit myself otherwise than expressed in the appended claims, certain of which are quite broad.

Having described my invention, what I claim as new, and desire to secure by Letters Patent, is—

1. In a type-writer, a type-wheel having on its exterior a plurality of type zones, type-

wheel vibrating and rotating mechanism, and means independent therefrom to rock said type-wheel about an axis transverse to the axis about which it rotates to bring either type zone into operative position.

2. In a type-writer, a rotary type-wheel having on its exterior type zones at different angles to its axis of rotation, key mechanism to change the direction of the axis of rotation of said type-wheel to bring either type zone into operative position, and type-wheel-vibrating mechanism independent of said key mechanism.

3. In a type-writer, a type-wheel having a plurality of type zones at different angles to its axis of rotation, a series of characters on each of said type zones, the series on different zones being different, a series of key-levers, means independent from the key-levers to bring either type zone into operative position, and means operated by said key-levers to rotate the type-wheel through different angles to bring any desired character into operative position and to vibrate said type-wheel.

4. In a type-writer, a type-wheel having a plurality of type zones thereon at different angles to its axis of rotation, one of said type zones bearing the small letters, another having the capital letters thereon, and another having figures or other characters, means to change the direction of the axis of rotation to bring either type zone into operative position, and type-wheel rotating and vibrating mechanism.

5. In a type-writer, a type-wheel having on its exterior a plurality of type zones at different angles to its axis of rotation, one of said type zones having small letters thereon, another of said type zones having capital letters, and another of said type zones having figures or characters, key mechanism to change the direction of the axis of rotation of said type-wheel to bring either type zone into operative position, and type-wheel-vibrating mechanism independent of said key mechanism.

6. In a type-writer, a type-wheel having a plurality of type zones at different angles to its axis, type-wheel-vibrating mechanism, and means independent therefrom to bring either type zone into operative position.

7. In a type-writer, a type-wheel having a central, cylindrical type zone, and at either side thereof a conical type zone, and type-wheel-vibrating mechanism.

8. In a type-writer, a rotary type-wheel having a central, cylindrical surface, and a conical surface, each of said surfaces having letters or characters thereon, means to bring either of said surfaces into operative position, and type-wheel-vibrating mechanism.

9. In a type-writer, a rotary type-wheel having a central, cylindrical type-surface, and a conical type-surface, key mechanism to bring either type-surface into operative position, and type-wheel-vibrating mechanism.

10. In a type-writer, a rotary type-wheel having a central cylindrical type-surface, and at either side thereof a conical type-surface, means to swing said type-wheel to bring either type-surface into operative position, and type-wheel-vibrating mechanism. 5
11. In a type-writer, a vibrating rotary type-wheel having a central, cylindrical type-surface, and at either side thereof a conical type-surface, means to swing said type-wheel about a transverse axis to bring either type-surface into operative position, and type-wheel rotating and vibrating mechanism. 10
12. In a type-writer, a vibrating rotary type-wheel having a central, cylindrical type-surface, and at either side thereof a conical type-surface, key-lever mechanism to swing the said type-wheel about a transverse axis to bring either type-surface into operative position, and type-wheel 15 rotating mechanism independent therefrom. 20
13. In a type-writer, a vibrating arm, means carried thereby to support a type-wheel for turning movement in two directions, key mechanism for turning the said type-wheel about its axis and vibrating said arm to bring the said wheel in contact with the paper, and independent key mechanism to change the direction of the axis of the type-wheel relative to the vibrating arm. 25
14. In a type-writer, a rotary type-wheel having a plurality of type zones at different angles to its axis, a shaft upon which said type-wheel rotates, a frame supporting said shaft, said frame being pivotally mounted upon an axis transverse to the axis of the type-wheel, key mechanism for controlling the frame, and type-wheel rotating and vibrating mechanism. 30
15. In a type-writer, a type-wheel having a plurality of type zones at different angles to the axis of said wheel, a yoke carrying a spindle on which said type-wheel rotates, said yoke being pivotally mounted on an axis 35 transverse to the axis of the type-wheel, a key-lever connected to said yoke, whereby the same may be turned to bring either type zone into operative position, and type-wheel-vibrating mechanism. 40
16. In a type-writer, a rotatable type-wheel having a plurality of type zones at different angles to its axis, a yoke having a spindle on which said type-wheel rotates, said yoke being pivotally mounted on an axis transverse 45 to the axis of the type-wheel, a key-lever, connections between the same and the yoke, a stop limiting the movements of said key-lever, a supplemental key-lever pivotally mounted on the first-named key-lever, a stop 50 for the supplemental key-lever, said stops being of different heights, whereby the depression of the main key-lever and supplemental key-lever operates to bring different type-surfaces into operative position, combined with type-wheel-vibrating mechanism. 55
17. In a book type-writer, a base, a carriage 60 slidably supported thereon for movement longitudinally thereof, and printing mechanism slidably supported on said carriage for movement transversely of said base, said printing mechanism including a vibrating arm, a type-wheel pivotally supported thereon for movement about both a longitudinal and transverse axis, means to turn said wheel about its transverse axis, and type-wheel-vibrating 65 mechanism. 70
18. In a type-writer, a vibrating arm, a type-wheel supported thereby for movement about both a longitudinal and transverse axis, a pinion on said arm, connections between 75 said pinion and type-wheel, said connections including a universal joint, key-lever mechanism for rotating the pinion and vibrating the arm, and means to turn the type-wheel on its transverse axis. 80
19. In a type-writer, a vibrating arm, a type-wheel supported thereby for movement about both its longitudinal and transverse axis, a pinion on said arm, a slotted arm having pivotal connection with the pinion, a pin 85 on said type-wheel engaging said slot, means for rotating the pinion, to thereby rotate the type-wheel and vibrating mechanism for the arm, and means to swing the type-wheel on its transverse axis. 90
20. In a book type-writer, a base, printing mechanism movable both longitudinally and transversely of said base, said printing mechanism comprising a rotary type-wheel having a plurality of type zones at different angles to its axis, means to bring any type zone into operative position, and type-wheel-vibrating mechanism. 95
21. In a book type-writer, a base, a carriage 100 slidably mounted thereon, printing mechanism supported on said carriage, said printing mechanism comprising a rotatable type-wheel having a plurality of type zones at different angles to its axis, means to bring any type zone into operative position, key-levers, 105 means operated thereby to vibrate the type-wheel, combined with mechanism to advance the printing mechanism to form spaces between letters, said mechanism comprising a rack fast to the carriage and a reciprocating 110 pawl on the printing-mechanism frame, and means common to all the key-levers to reciprocate the pawl. 115
22. In a book type-writer, a type-wheel having a plurality of type zones theron at different angles to its axis, means to normally hold one of said type zones in operative position, key-lever mechanism to bring either of the type zones into operative position, and type-wheel-vibrating mechanism. 120
23. In a book type-writer, a base, a carriage 125 slidably supported thereon for movement longitudinally thereof, and printing mechanism slidably supported on the carriage for movement transversely of said base, said printing mechanism including a rotatable type-wheel having on its surface a plurality of type 130

zones, type-wheel rotating and vibrating mechanism, and means independent therefrom to rock said type-wheel about an axis transverse to the axis about which it rotates to bring either type zone into operative position.

In testimony whereof I have signed my

name to this specification in the presence of two subscribing witnesses.

CHARLES E. MAXWELL.
